SAMUEL LEWIS, OF WILLIAMSBURG, NEW YORK.

3

Letters Patent No. 103,899, dated June 7, 1870.

IMPROVEMENT IN SUBMARINE DRILLING APPARATUS.

The Schedule referred to in these Letters Patent and making part of the same.

To all whom it may concern:

Be it known that I, SAMUEL LEWIS, of Williamsburg, in the county of Kings and State of New York, invented a new and useful Improvement in Submarine Drilling Apparatus; and I do hereby declare that the following is a full, clear, and exact description thereof, which will enable others skilled in the art to make and use the same, reference being had to the accompanying drawing forming part of this specification.

The figure is a detail sectional view illustrating my invention.

My invention has for its object to furnish an improvement in the apparatus for raising the boat or other floating platform from which a gang of drills is operated, so that it may be unaffected by the rise and fall of the tide; and

It consists in the construction and combination of the various parts of the apparatus, as hereinafter more fully described.

A represents the frame-work of the boat or float through which the spuds or vertical anchors B are passed, by and upon which spuds, the said boat or platform is supported.

The spuds B pass down through a guide-hole in the deck or other part of the boat, and through a well-hole in the lower part of said boat.

Upon the opposite sides of the spuds B are formed rack-teeth, as shown in the drawing, into which the teeth of the pawls C, pivoted to or connected with the cross-beam or head D, and the toothed pawls E, pivoted to or connected with the cross-beam F, fit.

G are strong hollow cylinders, the lower ends of which are securely connected with the frame-work A of the boat, and the upper ends of which are securely connected with the ends of the cross-beam or head D, through which they pass.

H are piston-rods working through the stuffing-boxes in the upper heads of the cylinders G, and to the lower ends of which are attached pistons, working in the said cylinders.

The upper ends of the piston-rods H are securely attached to the ends of the cross-beam or head F.

I are small pipes, leading into the upper parts of the cylinders G above the pistons, and

J are small pipes, leading into the lower parts of the cylinders G below said pistons.

The pipes I and J are both connected with a hydraulic pump and with the water-cistern, so that the lower pipes may serve as discharge-pipes when the water is being forced through the upper pipes I into the upper parts of the cylinders G, and so that the upper pipes I may serve as discharge-pipes when the water is being forced through the lower pipes J into

the lower parts of said cylinders below the said pistons.

The pawls C and E may be operated to throw them into and out of gear with the spuds B, by levers or other convenient means.

In using the apparatus, supposing the boat to be floating upon the water in the proper position and the spuds to be lowered till their lower ends rest upon the solid bottom, to raise the boat so that it may be unaffected by the rise and fall of the tide, the pawls B are thrown out of gear with the spuds B and the water forced into the lower part of the cylinders G below the pistons, raising the cross-head F. The pawls E are then thrown into gear with the spuds B, and the water is forced into the upper parts of the cylinders G, forcing or tending to force them down, but, as they are connected with the cross-head F, and that with the spuds B by the pawls E, they cannot move downward, and the cylinders G are made to rise, carrying the boat with them.

When the stroke has been completed, the pawls C are thrown into gear with the spuds B to hold the boat suspended, the pawls E are thrown out of gear with the spuds B, and the water is again forced into the lower parts of the cylinder to again raise the cross-head F, and so on until the boat or platform A has been raised to the desired height. By reversing this operation, the boat may be lowered to again rest upon the water.

Having thus described my invention,

I claim as new and desire to secure by Letters Patent—

1. The combination of two sets of pawls C E with the spuds or vertical anchors B; for alternately grasping said spuds while the boat or platform is being raised and lowered, substantially as herein shown and described.

2. The combination of two or more pistons and piston-rods H and cylinders G, provided with ingress and discharge-pipes I J, with the boat or platform A and spuds or vertical anchors B, substantially as herein shown and described, and for the purpose set forth.

3. The combination of the cylinders G, provided with ingress and discharge-pipes I J, piston and piston-rods H, cross-heads or beams D and F, and pawls C and E, with the boat or platform A and spuds or vertical anchors B, substantially as herein shown and described, and for the purpose set forth.

The above specification of my invention signed by me this 11th day of September, 1869.
